UNITED STATES PATENT OFFICE

111,022

DESIGN FOR A DRESS

Sylvia Epstein, New York, N. Y.

Application July 11, 1938, Serial No. 78,387

Term of patent 3½ years

To all whom it may concern:

Be it known that I, Sylvia Epstein, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the specific combination of the embroidery and lace edgings arranged on the pockets and darted sleeves of the particular dress, as shown.

I claim:

The ornamental design for a dress, substantially as shown and described.

SYLVIA EPSTEIN.
